United States Patent Office.

STARR POLLEY, OF BROOKLYN, NEW YORK.

Letters Patent No. 82,748, dated October 6, 1868.

IMPROVEMENT IN MACHINES FOR STRETCHING AND BLOCKING HATS.

The Schedule referred to in these Letters Patent and making part of the same.

TO ALL WHOM IT MAY CONCERN:

Be it known that I, STARR POLLEY, of Brooklyn, county of Kings, and State of New York, have invented certain new and useful Improvements in Hat-Stretching Machines; and I do hereby declare that the following is a full and exact description thereof.

My invention is based on that described in a patent issued to me, dated April 2, 1867. It relates to the means of holding the hat upon the stretching-device. I employ an India-rubber band in place of the clamps described in my former patent. The band holds the hat properly, and reduces the complication of the mechanism, as thereby its cost, and the labor of keeping it in order, and is found in practice to be more desirable in its effect upon the hats. The band is also capable of performing an important function in relation to the hat, after the latter has been removed from the stretching-machine. In other words, my invention, although designated an improvement in hat-stretching machines, (by which I mean the operations known as stretching, steaming-on, &c.,) relates not only to the machinery for and the operation of stretching, but also to the subsequent treatment of the hat while it is held on the block.

Rubber bands have been before used on stretching-machines, but never, as I am aware, so as to clamp or hold the hat-body upon the stretching-device, nor to hold the hat or hat-body properly upon the hat-block during any of the subsequent stages.

I will first describe what I consider the best means of carrying out my invention, and will afterwards designate the points which I believe to be new.

The accompanying drawings form a part of this specification.

Figure 1 is a central vertical section, and

Figure 2 is a plan view of the entire machine. Fig. 1 shows the machine with a hat-body in place, and with all the parts in condition ready to commence the stretching-operation. Fig. 2 shows the levers in the same position, but without the hat-body and without the hollow cylindrical band of elastic material which forms the peculiar novel element in the apparatus.

Figure 3 is a vertical section through the said band and the adjacent parts, after the levers have been moved apart to stretch the tip.

Figure 4 shows the same, after the block has been raised, and the hat-body with the said band drawn upon it; and

Figure 5 shows the hat-block and band with the hat-body, after being removed from the stretching-levers and placed upon a stand, which may be at any required distance from the stretching-mechanism. It is ready for the subsequent treatment.

Similar letters of reference indicate like parts in all the figures.

A is a rigid framework.

B is a series of levers, turning on hinges, b, and provided with springs, C, which tend to hold the upper ends of the levers close together.

D are cords or chains, leading to the treadle E, turning on a hinge, e.

The operation of all these parts is as described in my former patent. The hat-body f is applied over the upper ends of the levers, and the treadle being depressed, the levers are extended and stretch the hat.

O is a block, mounted on a carrier, N, and operated by the lever P, through the aid of the cord R and its connections, as represented. By turning the lever P, the cord R is pulled up, and the hat-block is elevated into contact with the stretched top of the hat. Turning the lever P still further, the hat-block is pushed up with force, so as to draw up the hat-body and to cause it to embrace the block tightly. The block O, with the hat upon it, is finally taken off by hand, or otherwise removed for subsequent treatment, while another block, O, is placed on the carrier N and depressed, after which all the parts are allowed to return to their original position, and another hat-body is applied.

T is a band of vulcanized rubber. It is made of such size that it fits easily upon the hat-body, in the posi-

tion indicated in fig. 1, and fits tightly, so as to clasp it with considerable firmness when the stretcher-levers B are extended, as indicated in fig. 3. When the levers B begin to separate at their upper ends, the rubber band holds the hat-body, and prevents it from sliding upward on the levers, but after the hat-block has commenced to draw the hat-body upward, the rubber band moves with the latter, and ultimately slips off of the upper end of the levers, and embraces the hat-body upon the hat-block O alone, as indicated in figs. 4 and 5.

It will be readily understood that the blocks O may be changed to different sizes and styles, and that the rubber band T may be changed in diameter, as also in width, to adapt it to different sizes and styles of work.

After the hat is upon the block, as in fig. 5, the rubber band holds the hat tightly and takes the place of the string, which has generally been considered necessary in this part of the operation. A string may be applied in addition to the band, in any case, if preferred.

The hat may be treated, in all the subsequent stages, in the same manner as when stretched, steamed on, blocked, &c., by other and ordinary means.

I have described the bands T as rubber. Any of the compounds of rubber, gutta-percha, or analogous material, may be employed, which will endure the heat of the steam or hot water, and will possess the high elastic tension which is required. I prefer soft vulcanized rubber. It is important, whatever the material employed, that the band shall be made of considerable width in the vertical direction, and it is important, in the subsequent treatment, that it be of little thickness radially. In other words, it should be a flat band, in the form of a hollow cylinder, rather than that of an annular piece cut from a disk.

Having now fully described my invention, what I claim as new, and desire to secure by Letters Patent, is as follows:

1. I claim the arrangement of the flat elastic ring or band T, of rubber, over or outside of the hat-body f, as shown and described, in combination with the stretching-device B, when arranged to operate relatively thereto during the stretching operation, substantially as and for the purposes herein set forth.

2. I claim the elastic band T, in combination with a hat-body, and with the block O and stretching-device B, so as to perform the double function of clamping or holding the hat-body in place upon the stretching-machine in the act of stretching the tip, and also of holding the body upon the block during the subsequent operation, substantially as herein described.

In testimony whereof, I have hereunto set my name in presence of two subscribing witnesses.

STARR POLLEY.
